E. D. EBY

ENCASED TRANSFORMER

Filed May 8, 1923

Inventor:
Eugene D. Eby,
by *Wm. S. Lewis*
His Attorney.

UNITED STATES PATENT OFFICE.

EUGENE D. EBY, OF PITTSFIELD, MASSACHUSETTS, ASSIGNOR TO GENERAL ELECTRIC COMPANY, A CORPORATION OF NEW YORK.

ENCASED TRANSFORMER.

Application filed May 8, 1923. Serial No. 637,562.

To all whom it may concern:

Be it known that I, EUGENE D. EBY, a citizen of the United States, residing at Pittsfield, in the county of Berkshire, State of Massachusetts, have invented certain new and useful Improvements in Encased Transformers, of which the following is a specification.

My invention relates to encased transformers. The general object of the invention is to provide an improved arrangement and construction resulting in compactness, minimum weight and reduced cost as compared with present practice. The invention is of particular application in connection with high tension transformers of small current capacity such as the current or instrument type of transformer.

High tension transformers are commonly immersed in an insulating liquid within a metal casing provided with insulating bushings for the transformer leads extending through the cover of the casing, in order to provide suitable distance to prevent arcing between the transformer windings and leads and the metal cover and upper portion of the wall of the casing. This necessitates a relatively tall casing in order that its cover may be spaced a considerable distance above the transformer windings and in order that there may be sufficient space available under the cover for the lower ends of the bushings. In accordance with the invention, the upper portion of the transformer casing has the general form of the usual high tension insulating bushing but made large enough to surround the upper portion of the transformer and provided with means at an opening at its top for supporting the high tension leads of the transformer. Among the advantages of this construction are minimum height and weight with a consequent low cost and convenience in handling. A further advantage is the avoidance of the necessity for separate high tension bushings for the high tension transformer leads.

Further objects and advantages will be apparent from the following description taken in connection with the accompanying drawing in which Figure 1 is a view, largely in vertical section, of an encased oil immersed current or instrument transformer arranged in accordance with the invention, and Fig. 2 is a sectional view on the line

2-2 of Fig. 1 of the upper part of the encased transformer.

Like reference characters refer to similar parts in both figures of the drawing.

The particular embodiment of the invention shown in the drawing includes a high tension current or instrument transformer having a core 1 with a high tension winding 2 and a low tension winding 3. The transformer is immersed in an insulating liquid within a casing comprising a metal base portion 4 and an upper portion 5 of moulded insulating material such as porcelain. The core 1 is disposed horizontally and supported by a plate 7 secured in the joint between the two portions 4 and 5 of the casing so that the transformer core and windings are supported by the upper rim of the lower portion 4 of the casing. The core 1 has three legs, the center one being surrounded by the windings 2 and 3. The high tension winding is insulated from the low tension winding and core by high tension bushings 6 extending suitable distances above and below the core. The high tension winding 2 and its bushings extend considerable distances above and below the core 1 and the low tension winding 3 in order that the parts of the high tension winding exposed between the ends of the bushings may be sufficiently spaced from all other parts which operate at lower potential. The leads from the high tension winding are carried out through a cover which is in the form of an outlet member provided with outlet bushings 9 and a hand hole cover 10. The transformer is immersed in suitable insulating liquid which fills the main casing and extends up into a compartment 11 in the lower part of the outlet member 8 where the level of the liquid may arise and fall to accommodate expansion and contraction due to varying temperature conditions.

The construction which has been described permits the insulating portion 5 of the casing to be tapered toward its upper end. This is of advantage in reducing considerably the size and weight of the casing and also the amount of insulating liquid necessary for proper immersion of the transformer.

What I claim as new and desire to secure by Letters Patent of the United States, is:—

1. The combination with a high tension

- transformer of a casing therefor, the wall of said casing comprising a lower metallic section and an upper insulating section, the transformer comprising a horizontally disposed core supported by said lower metallic wall section near its upper edge, high tension bushings extending from the space within said lower metallic wall section through said core into the space within said upper insulating wall section, the transformer having a high tension winding extending through said bushings, and an outlet cover at the upper end of said casing wall.
- 5 2. The combination with a high tension transformer of a casing therefor, the wall
- of said casing comprising upper and lower sections, said upper wall section being of insulating material, a support for said transformer extending into the joint between 20 said wall sections whereby said transformer is supported by the upper edge of said lower wall section, said transformer having a high tension winding extending downwardly into the space within said lower 25 wall section and upwardly into the space within said upper insulating wall section, and an outlet cover at the upper end of said casing wall.

In witness whereof, I have hereunto set 30
my hand this 2nd day of May, 1923.

EUGENE D. EBY.
